UNITED STATES PATENT OFFICE.

HEMAN W. MCKENZIE AND RUFUS L. MALTBA, OF BLACK EARTH, WISCONSIN.

DISHWASHING MACHINE.

Application filed March 31, 1922, Serial No. 548,336. Renewed April 9, 1925.

To all whom it may concern:

Be it known that we, HEMAN W. MCKENZIE and RUFUS L. MALTBA, citizens of the United States, residing at Black Earth, in the county of Dane and State of Wisconsin, have invented a new and useful Dishwashing Machine, of which the following is a specification.

This invention relates to a machine for washing dishes and the like, one of its objects being to provide a container having novel means therein for projecting water to all parts of the container so that every article within the machine will be acted on by the water and the thorough cleansing of the contents is insured.

A further object is to provide means whereby practically the entire body of water contained in the machine is projected upwardly over the contents, the projection taking place in successive impulses so that less power is required to operate the machine than would be necessary should the entire liquid contents be thrown upwardly at one impulse.

With the foregoing and other objects in view which will appear as the description proceeds the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a vertical transverse section through the machine.

Figure 2 is a section on line 2—2, Figure 1, said section being on an enlarged scale.

Referring to the figures by characters of reference 1 designates a container of any suitable proportions and provided with an inclined bottom 2 extending downwardly to a longitudinal trough 3 which is concentric with a shaft 4 journaled in the end walls of the container. Secured to the walls of container 1 are cleats 5 adapted to support a foraminous basket 6 intended to fit snugly

within the container but being readily removable therefrom. A cover 7 is mounted on the container.

Mounted on the shaft 4 so as to rotate therewith is a sleeve 8 on which are provided circular disks 9 spaced apart regularly and projecting into the trough 3. A projecting blade 10 is arranged between every two disks and the blades are all out of alignment and are arranged around the shaft in a spiral series. The shaft 4 and the parts mounted thereon can be rotated in any suitable manner, as by means of a belt driven pulley 11.

In using this machine a quantity of hot water having a cleansing substance mixed therewith is supplied to the container so that the level thereof will be below the cleats 5. The basket 6 with the articles therein to be cleaned is lowered into the container, the cover 7 is placed in position, and the shaft 4 is rotated at a high speed. This will cause the blades 10 to successively project the water upwardly from the trough through the bottom of the basket 6 and over the contents of the basket, one rotation of the shaft being sufficient to project water from the trough throughout the length thereof. A thorough agitation of the water is thus effected and the contents of the basket will be efficiently cleansed. After this operation has been completed the dirty water can be drained from the container through a valved outlet 12 after which a supply of clean hot water can be placed in the container and the foregoing operation repeated.

Thus the dishes will be thoroughly rinsed and by removing the basket the contents thereof will drain and dry without further treatment.

By referring particularly to Figure 1 it will be noted that by having the bottom of the container inclined as at 2 each blade 10 will not only throw water upwardly through that portion of the basket directly over the trough but will also throw it laterally throughout the width of the bottom 2.

What is claimed is:

In a rotary splasher for throwing a cleansing liquid against the contents of a dishwashing machine, a shaft revolvably mounted longitudinally within and adjacent the bot-

tom of a container, discs secured to and spaced at intervals longitudinally of the shaft, plates extending from disc to disc and secured radially between the same and formed in a spiral along the shaft, so that a liquid will be projected upward and laterally from the splasher, in combination with a liquid container having a vertical front

wall, a curved lower front corner, an inclined bottom and vertical rear wall, and means for revolving the splasher.

In testimony that we claim the foregoing as our own, we have hereto affixed our signatures.

HEMAN W. MCKENZIE.
RUFUS L. MALTBA.
